UNITED STATES PATENT OFFICE.

ALEXANDER T. BROWN, OF SYRACUSE, NEW YORK, ASSIGNOR TO THE BROWN-LIPE GEAR COMPANY, OF SYRACUSE, NEW YORK, A CORPORATION OF NEW YORK.

VALVE MECHANISM FOR INTERNAL-COMBUSTION ENGINES.

Specification of Letters Patent. Patented July 18, 1916.

1,191,150.

Application filed January 20, 1908. Serial No. 411,585.

To all whom it may concern:

Be it known that I, ALEXANDER T. BROWN, of Syracuse, in the county of Onondaga and State of New York, have invented a certain new and useful Valve Mechanism for Internal-Combustion Engines, of which the following is a specification.

My invention relates to valve mechanisms for internal combustion engines, and it aims particularly to provide an arrangement for controlling the inlet and the exhaust of the explosive mixture and residuum of combustion, respectively, which is particularly simple in construction and highly efficient in use.

The invention includes the parts and the combination and arrangement of parts to be hereinafter described, and particularly pointed out in the claim.

In describing this invention, reference is had to the accompanying drawing in which like characters designate corresponding parts in all the views.

Figure 1 is a fragmentary view of the outer end portion of an air-cooled cylinder equipped with one embodiment of my invention, the parts being shown in transverse sectional elevation. Fig. 2 is a similar view illustrating a modified embodiment of my invention.

The invention includes generally, an engine cylinder having a single opening through the inner end, or head, thereof constituting both an inlet and an exhaust passageway, a single valve controlling said opening and constituting the sole movable means for sealing the end of the cylinder, separate inlet and exhaust passages leading to and from the opening, and an auxiliary valve controlling one of said passages, establishing communication between the other and the opening and coöperating with the first-named valve.

In the exemplification of the invention illustrated, the piston chamber *a*, of the engine cylinder, is of truncated conoidal shape at its inner end, and this end of the cylinder is provided with an axial opening *a'* leading entirely therethrough and having an outwardly-flaring wall. This opening is preferably of maximum diameter, and in the particular structure illustrated, is of approximately one-half of the maximum diameter of the cylinder.

In the particular exemplification of the

invention, illustrated in Fig. 1, the valve mechanism is a self-contained structure adapted to be secured to, and removed from, the engine cylinder as a unit, and it comprises a hollow casing *b*, preferably cast in one piece, provided with a diagonally-arranged diaphragm *c* dividing the chamber of the casing into two passages *f*, *g*, the upper one of which is in open communication at one end with a port *h* in one side wall of the casing, and the other of which is in open communication at one end with a port *i* in the opposite side wall of the casing. Both of the passages *f*, *g*, communicate with a third port *k* in a nipple or boss *l* which projects from the lower side of the casing, and has an inverted conical shape periphery snugly fitting the opening *a*, and a broadened beveled edge *m* providing a valve seat. The passageway *f* communicates with the port *k* through an opening *d* in diaphragm *c* and through a depending flange *e*, surrounding such opening, which terminates a distance from the inner wall of the nipple *l* and forms therewith an annular opening or port *g'* at the inner end of passageway *g*. The port *h* is designed to communicate with the exhaust of the engine and the port *i* is designed to communicate with the passageway leading from the carburetor or other suitable explosive mixture supply. Both the main valve and the auxiliary valve seat against the surface *m* and both valves have movement toward and from said seat in a direction axial of the cylinder.

The auxiliary valve *n* is provided with a hollow flaring head and with a tubular stem portion fitted to, and guided within, the flange *e*, and with a conical stem portion provided with orifices *n'* establishing open communication between the bore of said stem and the passageway *f*, and such conical portion of the stem terminates in a tubular stem portion *o* of relatively reduced diameter, which is guided in an opening located in the top of the casing and in the bore of a boss or flange surrounding said opening.

The main valve has a disk-shaped head *r* provided with a bevel periphery seating upon the surface *m* immediately in advance of the auxiliary valve *n*, this head being carried by a solid stem *r'* which is guided through the part *o*, of the auxiliary valve, and through a sleeve *o'* extending into the

cylindrical part of the stem. The stem r' projects beyond the end of the stem o and carries an inverted cup-shaped head s between which and the upper wall of the casing b , a helical spring t , is interposed which tends to hold the valve seated. A head u is also secured to the outer end of the stem o between which and the casing a second spring v is interposed for normally holding the auxiliary valve seated. The head u is preferably located and movable within the head s .

Suitable levers w , x , operated at the proper relative periods by mechanism associated with the crank shaft of the engine, are respectively engaged with the ends of the stems o , r' for depressing the same against the tensions of the springs t , v ; the end of the lever x extending through an opening in the head s to engage with the end of the stem o .

As will be understood, when the stem r' is depressed, the valve r will be unseated, but the valve n will remain seated and will close the inner end of passageway g , in consequence of which only the exhaust passageway f will be put into communication with the chamber a . It is apparent that an opening of maximum size for the escape of the residuum of the exploded charge is presented when the valve head r is unseated. When the stem o is depressed, the auxiliary valve will move from its seat, and in initial part of its movement will make contact with the rear face of the valve r , and during the remainder of its movement will carry the valve r along with it. The inner end of the passage g , or port g' is uncovered when the auxiliary valve is depressed, and the explosive mixture then rushes into the chamber a and in its passage thereto contacts with the valve seat m and the seating surface of the valve head r and serves to cool the same. The contact effected between the auxiliary valve and the main valve during the initial part of the movement of the former closes the passage through the auxiliary valve and thus cuts off communication between the engine chamber and the passageway f .

Although the valve mechanism has been shown and described as a self-contained structure separable as a unit from the engine cylinder, it will be appreciated that the valve casing might be made integral with the engine cylinder.

In Fig. 2 is illustrated a modified form of this valve mechanism in which the inlet and exhaust passages i^{10} and h^{10} are arranged on the same side of the boss or nipple l^{10} in-

stead of on opposite sides as in the construction shown in Fig. 1, and the auxiliary valve n consists of a hollow cylindrical head entirely open at its top and communicating with the passage f^{10} , said head being connected to its stem by webs r^{10} located near the bottom of the head.

What I claim is:

The combination of the main body of an engine cylinder, said body being provided with an opening through the head of the cylinder and a self contained valve mechanism comprising a hollow casing provided at its lower end with a boss for fitting said opening and with an internal nipple extending into the boss forming inner and outer passages located entirely within the casing, said casing extending above said main body and being provided at its upper end above the main body with a port communicating with the upper end of the inner passage and a port communicating with the outer passage through a side wall thereof, one port being the main exhaust port of the engine and the other being the main inlet port thereof, the casing being also provided with a port common to said passages and located at the inner end of said boss, a main valve controlling the common port and seating against the inner end of said boss, a second valve seating against the inner end of said boss and engaging the rear face of the main valve, the second valve having a tubular stem portion slidable within and fitting the nipple and a conical stem portion extending into the port communicating with the nipple, said conical stem portion having a passage in the side thereof, the passage opening into the last mentioned port, and the main valve being arranged to control the inner end of the passage of the tubular portion of the second valve and also the outer passage and having an axial stem projecting above the casing, and the inner valve terminating in a sleeve encircling said stem, and means coacting with the stem and the sleeve for actuating the valves together as a unit or for actuating the main valve independently of the second valve, substantially as and for the purpose specified.

In testimony whereof, I have hereunto signed my name in the presence of two attesting witnesses, at Syracuse, in the county of Onondaga, in the State of New York, this 14th day of January, 1908.
